UNITED STATES PATENT OFFICE.

DAVID D. BRINKERHOFF, OF MANCOS, COLORADO.

PORTABLE FENCE.

Application filed July 2, 1924. Serial No. 723,714.

This invention relates to improvements in portable fences, and the primary object of my invention is to provide a fence of this character which may be readily folded into 5 a compact roll for transporting or storing the same.

A further object of the invention is the provision of a fence of this character which may be readily and quickly placed in position 10 as a fence and be durably supported.

A still further object of the invention is the provision of a fence of this character having spring means associated therewith for retaining the same tight at all times but permitting 15 a slight yielding movement.

A still further object of the invention is the provision of a fence of this character which is comparatively simple in construction very durable, and efficient for this purpose. 20

Other objects and advantages of this invention will be apparent during the course of the following description.

In the accompanying drawings forming a 25 part of this specification and in which like numerals are employed to designate like parts throughout the same:

Figure 1 is a side elevation of a section of 30 my improved fence in position,

Figure 2 is a perspective view showing the method of connecting a corner thereof,

Figure 3 is an enlarged detail view of the connecting means,

Figure 4 is a top plan view of one of my 35 fence sections,

Figure 5 is an end elevation showing the means of bracing my improved fence.

Figure 6 is an enlarged detail view of the fence construction,

Figure 7 is a diagrammatic view illustrating 40 one method of employing any fence, and

Figure 8 is a similar view showing still another method of using my improved device.

In the drawings, wherein for the purpose 45 of illustration is shown the preferred embodiment of my invention, the numeral 10 generally indicates the supporting posts of my improved portable fence, these posts being

rectangular in cross section and pointed at 50 the lower end as shown at 11 to permit them to be readily forced into the ground. The upper extremities of the posts are provided

with metallic bands 12 adapted to prevent 55 splitting of the posts when being driven into the ground. In the form of my invention

illustrated in the drawings herewith I employ three such posts to each said section each post carrying a plurality of screw eyes 13 upon each of the narrow edges thereof. 60 Each of these screw eyes 13 is adapted to connect with the longitudinal strands of the fence proper; I consider it advisable to use about eight strands of this character for the ordinary type of fence. Each fence section 65 comprises a pair of fence panels composed of wires and springs as will hereinafter be described.

These panels comprise a plurality of longitudinal wires 14 having loops 15 formed 70 on the extremities thereof. These wires are connected by a plurality of plates, the type of plates employed on the upper and lower wire strands being substantially triangular in form as shown at 16 while the intermediate connecting plates are substantially 75 square as shown at 17, one extremity of each longitudinal strand in the fence panel carrying a coil tension spring 18 secured to the end wire and screw eye mounted on the post. 80 These springs will retain the longitudinal strands in comparatively tight alignment at all times in addition to permitting the panel to give under unusual impact thereby relieving the strain from the supporting posts 85 10. Vertical connecting wires 19 connect with the connecting plates and retain the longitudinal strands in proper alignment.

Each of the end posts carries connecting means mounted on the outer edges thereof, 90 one of the posts carrying a comparatively short strand of wire 20 looped at its extremities as at 21 to engage a screw eye 13 secured to the post and a ring member 22 secured to the free extremity of the wire 20. 95 The opposite post member carries a similar wire strand to which is secured a spring snap 23 adapted to engage the ring 22 and firmly secure the section. These corner connections as clearly shown in Figures 2 and 3 are 100 provided for the purpose of permitting connection of any number of fence sections, the number employed depending on the size of the closure it is desired to construct. It is also to be noted that the sections may also 105 vary in size, any number of posts and panels, therebetween, being constructed in each section.

As it is desirable in many instances to provide additional bracing means in fences 110 of this character, the upper extremities of the posts are provided with openings to per-

mit attachment of a rope or cable 24 which may engage a peg 25 forced into the ground adjacent the post and adjusted by means of a cross rod 26.

5 In using my improved fence, when it is desired to form a comparatively small enclosure as shown in Figure 7, a pair of sections may be readily employed and connected as shown, the end posts being connected 10 as shown in Figure 2, at an angular position. When it is desirable to provide a larger enclosure, as shown in Figure 8, any number of sections may be employed, readily providing any size enclosure desired. It 15 is to be noted that my improved fence will combine the durability of a permanent fence with the advantage of quicker construction and transportability.

It is to be understood that the form of my

invention herewith shown and described is 20 to be taken as the preferred example of the same, and that various changes as to the shape, size and arrangement of parts may be resorted to without departing from the spirit of the invention or the scope of the 25 subjoined claim.

Having thus described my invention, I claim:

A panel fence comprising a number of posts, each post provided with a series of 30 eyes upon opposite sides, wire panels each secured to the eyes upon one side of each post, and wire tension springs connecting each strand wire of each panel with the eyes of an adjacent post. 35

In testimony whereof, I have affixed my signature.

DAVID D. BRINKERHOFF.
